UNITED STATES PATENT OFFICE.

ADOLPH O. SCHAEFER, OF NEW YORK, N. Y.

DESIGN FOR A LEVER FOR TIGHTENING SAW-BLADES.

44,414.

Specification for Design.

Patented July 29, 1913.

Application filed March 21, 1913. Serial No. 756,021. Term of patent 7 years.

To all whom it may concern:

Be it known that I, ADOLPH O. SCHAEFER, a citizen of the United States, and a resident of New York, borough of Brooklyn, in the county of Kings and State of New York, have invented a certain new, original, and ornamental Design for a Lever for Tightening Saw-Blades, of which the following is a specification.

The accompanying drawing shows a perspective view of the lever.

I claim:

The ornamental design for a lever for tightening saw blades, as shown.

ADOLPH O. SCHAEFER.

Witnesses:

W.M. J. SMITH,
CHARLOTTE MOSS.
